SHOE BEATING MACHINE

Charles E. Hood, Lynn, Mass., assignor to United
Shoe Machinery Corporation, Paterson, N. J.,
a corporation of New Jersey

Application May 4, 1936, Serial No. 77,702
In Great Britain March 6, 1936

6 Claims. (Cl. 12—51)

This invention relates to machines having heated rotary members and is herein illustrated as embodied in a machine for beating the bottoms of lasted shoes to prepare them for the sole-laying operation.

Prior to attaching soles to shoes it has been customary to trim the lasted over portions of the uppers and to smooth out the wrinkles therein by beating the shoe bottoms in order that they may be sufficiently smooth to fit closely to the soles when the latter are attached. It is an object of the present invention to provide an improved pounding machine which will perform the operation referred to effectively and at the same time will be simple and economical in its construction and operation.

To this end and as shown, the invention provides a shaft upon which is mounted a beating roll having a recess in an end portion thereof and a friction member arranged to engage the walls of the recess for the purpose of heating the roll. Preferably and as illustrated, there is provided resilient means for forcing the friction member into the recess, said means being adjustable to vary the pressure of the member against the roll thereby to control the amount of heat generated. This mechanism is advantageous in that it provides a comparatively simple and inexpensive means for heating the roll.

These and other features of the invention are illustrated in the accompanying drawing, described in the following detailed specification, and will be pointed out in the claims.

In the drawing,

Fig. 1 is a plan view, partly in section, of a machine embodying one form of my invention;

Fig. 2 is a detail view illustrating the operation of the shank pounding roll; and

Fig. 3 is a detail view illustrating the operation of the forepart pounding roll.

As illustrated in Fig. 1 the machine comprises a horizontal shaft 10 mounted in bearings 12 in a frame 14, there being a pulley 16 for driving a shaft. The shaft carries a forepart pounding roll 18, a shank pounding roll 20, and a trimming wheel 22. The forepart pounding roll 18 is generally cylindrical in shape but has its periphery slabbed off to form a plurality of flat faces 24 which when the roll is in operation constitute pounding members. The roll is secured to the shaft for rotation therewith by means of a pin 26.

In operating upon the forepart of a shoe in view of the wrinkles formed partly around the toe during the lasting operation it is sometimes

difficult to smooth out the lasted over marginal portions of the upper. To overcome this difficulty the present machine is provided with means for heating the forepart pounding roll, thereby to facilitate the pounding operation. To this end the roll 18 is provided with recesses 28 in the ends thereof, the walls of which are adapted to be engaged by members 30 of fiber or other suitable material which, during the rotation of the roll generate heat by friction. The cooperating recesses and friction members are herein illustrated as being conical, but the use of hemispherical or other shapes is contemplated. The friction members 30 are slidably mounted upon the shaft 10 and are arranged to be forced inwardly into frictional engagement with the walls of the recesses 28. To accomplish this, the members 30 have outwardly extending hubs 34 secured by pins 32 to yokes 33 carried by levers 34 pivotally mounted at 36 upon the machine frame. The outer ends of the levers 34 are normally forced away from each other by a spring 38 mounted upon a rod 40 the ends of which extend through openings 42 and 44 in the levers. This arrangement is such that the spring is operative to force yokes 33 toward each other moving the friction members 30 inwardly into frictional engagement with the walls of the recesses in the roll.

To regulate the pressure exerted by the friction members against the roll and, consequently, the amount of heat generated, there is provided a nut 46 on a screw threaded portion 48 of the rod 40. This nut can be readily adjusted to vary the pressure of the spring 38. The rod 40 also carries nuts 50 which can be adjusted along the screw thread 48 to take up the slack between the two ends of the levers 34.

The shank beating roll 20 is of similar construction to the roll 18 in that it has a plurality of flat work-engaging surfaces 52. This roll, however, is smaller in size than the roll 18 and ordinarily need not be provided with any means for heating it.

The trimming roll 22 at the end of the shaft 10 may be of any suitable construction such as that of a type which has come into general use and which comprises a felt roll having a sandpaper strip secured to its periphery. Such a roll is adapted for use in removing surplus upper material from the shoe prior to the beating operation.

The machine is provided with a work rest 54 positioned adjacent to the roll 18 adapted to

support the shoe when the forepart is being operated upon.

In the operation of the machine the lasted shoe is presented to the trimming roll 22 to trim off surplus portions of the lasted over margins of the upper and the shoe is then presented to the forepart pounding roll 18 as illustrated in Fig. 3 in which the shoe 56 is presented to the underside of the roll so that the faces of the roll will move inwardly across marginal portions 58 of the upper to smooth them out. The heat which is generated by the frictional engagement of the members with the roll will facilitate this operation. After the forepart is beaten out the shoe is then presented to the shank pounding tool 20 as illustrated in Fig. 2 to smooth out the shank portion of the machine.

Having described the invention, what I claim as new and desire to secure by Letters Patent of the United States is:

1. A machine for operating upon shoes comprising a shaft, a smoothing roll secured to the shaft and having a recess in one end thereof, and means for heating the roll comprising an annular member movable longitudinally of the shaft, and means for forcing the member into frictional engagement with the wall of the recess.
2. A machine for operating upon shoes comprising a shaft, a roll secured to the shaft and having a recess therein surrounding the shaft, an annular member surrounding the shaft and mounted for movement axially of the recess, and means for forcing the member into frictional engagement with the wall of the recess to heat the roll.
3. A machine for operating upon shoes comprising a shaft, a beating roll secured to the

shaft for rotation therewith and having a conoidal recess in an end thereof, a conoidal friction member surrounding the shaft and mounted for movement longitudinally thereof, and resilient means for forcing the conoidal member into frictional engagement with the wall of the recess. 5

4. A machine for operating upon shoes comprising a shaft, a roll secured to the shaft for rotation therewith and having at each end thereof a conoidal recess extending coaxially of the shaft, conoidal friction members mounted coaxially with the shaft and arranged for movement into the recesses, and resilient means for forcing the conoidal members into frictional engagement with the walls of the recesses. 10 15

5. A machine for operating upon shoes comprising a rotatable shaft, a roll mounted upon the shaft and having recesses in the ends thereof, a pair of levers pivotally mounted upon the frame of the machine, friction members carried by ends of the levers and mounted within the recesses, and a spring positioned between the other ends of the levers arranged to force the friction members into engagement with the walls 20 25 of the recesses.

6. A machine for operating upon shoes comprising a rotatable shaft, a roll mounted upon the shaft, a pair of levers mounted upon the frame of the machine and having end portions 30 located at opposite ends of the roll, friction members secured to said end portions, a spring positioned between the other ends of the levers operative to force the friction members into engagement with the ends of the roll, and means 35 for adjusting the pressure exerted by the spring.

CHARLES E. HOOD.
